United States Patent Office.

CHENEY KILBURN, OF PHILADELPHIA, PENNSYLVANIA, ASSIGNOR TO
KILBURN & GATES, OF SAME PLACE.

Design No. 4,350, dated September 13, 1870.

DESIGN FOR THE BOXES FOR THE TOPS OF BUREAUS.

The Schedule referred to in these Letters Patent and making part of the same

I, CHENEY KILBURN, of Philadelphia, county of Philadelphia, State of Pennsylvania, have invented or produced a Design for Boxes for the Tops of Bureaus, of which the following is a specification.

Description of the Accompanying Drawing.

Figure 1 is a perspective view of a box made in accordance with my design;

Figure 2, a plan view of the same;

Figure 3, an enlarged sectional view of the edge of the box; and

Figure 4, a view of a modification.

General Description.

The first three figures of the drawing represent one of the short boxes which are usually secured at or near each end of the top of a bureau for the support of the standards to which the glass is hung.

My design consists in forming the fronts of such

boxes on a succession of curves, *a b c*, &c., so as to impart a wavy and graceful appearance to the same.

The same design may also be applied to longer boxes, such as shown in fig. 4, which are intended to extend entirely across the top of a bureau, so as to support both of the standards, instead of one only.

The molding or finish for the edge of the box may be of the character shown in fig. 3, or of other appropriate design.

I claim—

The design for boxes for the tops of bureaus, substantially as described, and as represented in and by the accompanying drawing.

In testimony whereof I have signed my name to this specification in the presence of two subscribing witnesses.

Witnesses: CHENEY KILBURN.

LOUIS BOSWELL,

WM. A. STEEL.
